Twentor,

John J. McDonald

UNITED STATES PATENT OFFICE

2,142,476

TEMPLLET AND OPERATING MEANS THEREFOR FOR THE MANUFACTURE OF CUFFS

John I. McDonald, Chicago, Ill., assignor to Progress Specialty Company, St. Joseph, Mo.

Application June 23, 1934, Serial No. 732,130
Renewed May 28, 1938

1 Claim. (Cl. 112—2)

This invention relates to templets and operating means therefor for the manufacture of cuffs and its object is to provide certain improvements on the templets and operating means therefor set forth in my Patents No. 688,961, dated December 17, 1901, and No. 1,251,677, dated January 1, 1918.

The present improvements relate, first, to the position of the row of teeth or rack on the templet, second, to the means for guiding and turning the templet; third, to the means for feeding or shifting the templet; fourth, to the combination of the teeth or rack with the templet feeding or shifting means; fifth, to certain other improved features and combinations, hereinafter described 15 and shown in the accompanying drawings, in which:—

Figure 1 is a front elevation of the templet, its feeding means, and cutter or knife blade operating means and so much of a sewing machine as 20 will illustrate the use of the present improvements, certain parts being broken away and in section;

Fig. 2 is an end view thereof;

Figs. 3, 4, 5 are detail plan views, respectively 25 showing the position of the templet at approximately the commencement, intermediate, and concluding positions of its travel during which stitching of the cuff-plies held by the templet is accomplished, certain parts being in dotted lines and other parts omitted;

Fig. 6 is a bottom plan view of the templet when closed;

Fig. 7 is a plan view of the templet, when open, showing the inner faces thereof;

Fig. 8 is a side view of the templet, when 35 closed;

Fig. 9 is a cross-section on line 9—9, Fig. 6;

Fig. 10 is a detail section on line 10—10, Fig. 6; and

Fig. 11 is a detail perspective view, broken away, 40 disclosing the means for operating the templet.

The present improvements have for their object to overcome defects in the templet, feeding mechanism, and the operation thereof, as proposed by the constructions disclosed in my Patents Nos. 688,961 and 1,251,677.

In the templets of the aforesaid patents the teeth of the rack are cut into the under-surface of the frame and consequently in operation travel 50 in immediate contact with the plate or table of the sewing machine. These teeth are of sharp-angled ratchet form and under the pressure necessarily exerted by the presser-foot of the sewing machine in order to keep the templet firmly closed 55 on the cloth plies contained therein and to maintain contact with the driving pawl beneath, considerable friction accompanies the movement, resulting in uneven progress, especially around the turns, and in wear on the parts. In principle, the 60 movement effected in my earlier construction is

analogous to that of saw-teeth passing over the parts under the templet. The result becomes evident in skipped stitches in the sewing and makes necessary close attention from, and frequent assistance by, the operator. 5

In the present improvements, the teeth in the templet are cut in the inner or vertical edge of the lower frame, the under-surface thereof is left smooth, and not only is the movement made uniform by driving the templet by a gear-pinion 10 meshing with the rack, but the energy required to propel the templet remains constant throughout its progress, resulting in higher speed, better stitching, smoother progress, and in connection with the improved guides, complete automatic 15 control of movement.

This arrangement prevents any disconnection of the feeding means for the templet. The presser-foot of the sewing machine adequately holds down the templet and yet need not exert 20 considerable pressure on the templet in order to prevent disengagement of the pinion and rack.

The pinion is turned in step-by-step fashion by a ratchet wheel connected thereto, which is operated by a reciprocatory feed bar carrying a pawl 25 that engages a tooth on said ratchet wheel and turns the wheel and pinion on each advance movement of the bar, the pawl idling on the pinion on the retrograde movement of the bar. The bar is operated by a rock-shaft which is rocked by a 30 cam on a shaft of the sewing machine driving means.

The knife-blade operating mechanism which trims the stitched edges of the cuff-plies is intermittently operated to effect trimming by a rock-shaft which is periodically rocked by a cam on a 35 shaft of the sewing machine driving means. This rock-shaft, according to my present improvements, is reversely rotated or snapped back, when released from the action of said operating cam, 40 by a spring coiled around the shaft, thereby to restore the knife-blade or cutter to normal, raised position.

While the same shaft carrying the knife-blade of Patent No. 688,961 is shown herein, it will be 45 understood that a relatively short shaft and its rock arm may be substituted and enclosed in a compact housing, to clear the bed of the machine free of obstruction.

Improvements are provided for guiding the 50 templet throughout its feed by the rack and pinion which insure accuracy of the line of stitching and its completion.

In that respect, the invention contemplates the use of the straight bar having the needle hole 55 as proposed by Patent No. 688,961, in combination with arc-shaped or curved guides, which co-operate with the straight and curved parts of the frame of the templet according to the position thereof, insuring that the templet carry out the 60

prescribed and predetermined path of travel necessary to stitching the plies of cloth held thereby. These improvements cause the templet to follow its path of travel without deviation, regardless of the speed of operation.

The curved parts on the machine which co-operate with the curved parts of the templet may assume the form shown, that of curved bars or strips, or, equivalent guiding means for the templet may be provided.

The feeding pinion is so positioned in relation to the straight bar having the needle hole that the frame of the templet is jointly held in position during its travel by said bar and pinion, insuring accuracy of travel of the templet, with resultant correctness of the line of stitching and trimming.

The templet comprises two similar frames 1, 2, having straight ends and sides and rounded corners and hinged together at 3.

A gear rack 4 is provided on the inner edge of frame 1, the teeth of which are disposed vertically when the templet is in use on the machine.

The frames have flat plates 5, 6 secured thereto. Struck-up gage lips 7 on one plate are adapted to enter slots 8 in the other plate. These lips are adapted to engage the inner edge of the plies of cloth 9 (Fig. 1) carried between the plates 5, 6 said plies being held by penetrating points or prongs 10 on one frame which enter holes 11 in the other frame (Fig. 7).

The bed of a sewing machine is shown at 12, the needle appears at 13, and the presser foot at 14.

The table 15 which is connected to the bed 12, serves as a support for the templet, as shown in Fig. 1, the presser foot 14 then engaging the frame 2 of the templet to hold it down while the templet is fed, as the work of stitching and trimming the plies 9 progresses.

Depending from the bed 12 is a hanger 16 to which is secured a bracket 17 (Figs. 1, 2, 3). Journaled in a bearing provided on said bracket is a vertical shaft 18 whose upper part is journaled at 19 in table 15. Shaft 18 carries a ratchet wheel 20 at its lower part and a pinion 21 at its upper end.

The pinion 21 is adapted to mesh with rack 4 on the templet when the latter is placed on the table 15 and the end of frame 1 entered between the straight bar 22 and said pinion, as shown in Fig. 3.

When arranged, as described, operation of pinion 21 will cause feeding of the templet, in step-by-step manner, the templet advancing as shown in Fig. 4 and finally arriving in the Fig. 5 position, whereupon the templet may be removed.

During the feed of the templet, the needle 13 has stitched the cuff and the raw edges of the cuff-plies 9 have been trimmed by the knife-blade or cutter 23, Figs. 1 and 2.

The templet is fed in a straight line when either of its ends or its side is disposed between the pinion 21 and straight bar 22.

To turn the templet, as illustrated in Figs. 4, 5, curved surfaces are provided on table 15 corresponding in curvature to the curved or rounded corners of the templet. As shown in Figs. 3, 4, 5, these surfaces are provided by curved strips 24, 25 fastened to the top surface of table 15 in any suitable manner. The curved surfaces 26 of strips 24, 25, engage the rounded inner corners

27, 28 of the frame 1 to effect the turning movement. In lieu of strips 24, 25 a plate with rounded corners may be fastened to the top of table 15, the rounded corners corresponding to the curved surfaces 26. In a construction of that character the pinion 21 may be disposed in countersunk relationship to the superposed plate.

The pinion 21 will remain in mesh with rack 4 under the most rapid operation to which the machine will be subjected, and this improvement overcomes the defects of the templet feed mechanism of my Patent No. 688,961.

Suitably journaled below the bed 12 is a rock-shaft 29 (Fig. 1) which is operated by a cam on the sewing machine driving means. Adjustably secured to shaft 29 is an arm 30 (Fig. 11) to which is pivoted at 31 a pusher-bar 32 whose other end is loosely mounted in a slotted stirrup or hanger 33. The bar 32 carries a springy pawl 34 whose free end is adapted to engage a tooth of ratchet wheel 20 on the advance movement of pusher-bar 32 for the purpose of turning shaft 18 but on the retrograde movement of the bar 32 the inherent springiness of said pawl enables it to slip backwardly over the ratchet wheel without turning the shaft 18. The to-and-fro movements of the bar 32 cause a step-by-step turning of shaft 18 and advance of the templet in like manner.

The cutter or knife-blade 23 is carried by a shaft 35 mounted in suitable bearings 36 and carrying a rock arm 37 which is operated by a cam 38 on a shaft 39 mounted in bearings under the bed 12 and operated by a cam from the drive shaft of the sewing machine. A spring 40 coiled around shaft 39 and connected at its respective ends to the shaft and to the frame of the machine, turns the shaft 39 after the cutter 23 has been operated by the parts 31, 38 thereby restoring the cutter to its raised position.

In lieu of the shaft 35, the operating means for the cutter 23 may be compactly arranged within a small housing disposed near the cutter, thus leaving the bed 12 free of obstruction.

The cutter 23 co-operates with the bar 22 to effect a shear-cut of the raw edges of the cloth, as in Patent No. 688,961.

Operation: The closed templet, provided with the plies of cloth for making a cuff, is laid flat-wise on table 15 and the rack 4 engaged with pinion 21, as shown in Fig. 3. The raw edges of the cloth then overlie the bar 22, as in Fig. 1.

The presser foot 14 is then let down onto the templet and the work of stitching the cuff proceeded with. The pinion feeds the templet as illustrated in Figs. 3, 4, 5, turning being effected by the curved surfaces 26. The stitched edges of the plies are trimmed by the cutter 23.

When the stitching operation is completed, the templet is removed and another templet, or the same one, provided with another set of cloth plies, is used and the foregoing operations are repeated.

What I claim is:

In a sewing machine, feeding means for a work-carrier, comprising a feed pinion for operating the work-carrier, a ratchet wheel for turning the feed pinion, a reciprocatory pusher-bar, a pawl carried by the pusher-bar and intermittently engageable with the ratchet wheel to turn the pinion step-by-step, and means for reciprocating the pusher-bar.
